UNITED STATES PATENT OFFICE

JOHN W. ONG, OF MOUNT PLEASANT, OHIO

SHIFTABLE TRAY FOR BANK WINDOWS

Application filed April 10, 1928. Serial No. 269,000.

This invention relates broadly to safety windows for banks and ticket offices, and more specifically to a shiftable tray for such windows.

The primary object of the invention is to provide, in association with a window of that class employed in bank tellers' and ticket sellers' cages or booths, which embodies a pane of non-shatterable, bullet proof glass, a counter tray in which may be deposited money, pass books, or other articles, said tray being conveniently shiftable beneath said pane for transferring therein-deposited articles from one side of said pane to the other.

15 In describing the invention in detail, reference is herein had to the accompanying drawings, in which—

Figure 1 is a cross section of the window, showing the invention in top plan with the transfer tray disposed on the inner side of the window;

20 Figure 2 is a similar view showing the transfer tray on the outer side of the window;

25 Figure 3 is an under side elevation with the parts disposed as in Fig. 1, the shift plate being shown partially broken away;

Figure 4 is an under side elevation with the parts disposed as in Fig. 2, the shift plate and part of the operating lever being shown removed and the positions thereof being indicated in dot and dash lines; and—

30 Figure 5 is a section on line 5—5, Fig. 2. Referring to said drawings, 1 designates the usual pilasters located at opposite sides of a cashier's or teller's window which is located over a deal table or counter 2 at which the cashier or teller stands.

40 Fitted in the window opening between the pilasters 1 is a pane 3 of transparent bullet-proof glass which is disposed with its lower edge in substantially the plane of the top of the deal counter 2.

45 Provided in the deal counter beneath said glass pane 3 is an opening 4 of suitable dimensions within which is permanently fitted a rectangular frame consisting of side members 5 and end members 6, the latter having 50 horizontal top flanges 6^a which rest in

countersinks provided therefor in the top of the deal counter. Slidably disposed in overlying relation to the top surfaces of said flanges 6^a and the adjacent portions of the counter are oppositely disposed horizontal 55 plate-like flanges 7 and 8 formed on the inner and outer edges of a trough-like tray 9. Said tray, which is designed for the reception of money, pass books, and the like, is shiftable beneath the glass pane 3 to a position located 60 on either side of the latter, as desired, the same having its supporting flanges 7 and 8 freely slidable upon the adjacent surfaces of the counter.

Mechanism for actuating movement of the 65 tray back and forth from one side of the window to the other, whereby transfer of money and other articles is effected, comprises an operating lever 10 and a series of links and levers interposed between said lever 70 10 and the tray. The transfer mechanism herein shown for purposes of illustration includes a horizontal longitudinally disposed bar 11 which underlies the frame adjacent to one of its sides and which has upright end 75 portions fixed to the frame ends 6, as shown in Figs. 3 and 4.

Said bar constitutes a support upon the under side of which, at an appropriate point, is provided a pivot pin or bolt 12 for the support of the operating lever 10 which is adapted to be swung horizontally beneath the inner edge of the deal counter. Rigidly attached to said lever, as by bolts 13 and 14 is one edge of a horizontally disposed guide member 15 80 which may be of flat plate form and which, as herein shown, is provided adjacent to its opposite edge with two suitably shaped guide slots 16 and 17 in which are disposed anti-friction rollers 18 and 19 carried, respectively, by the relatively approaching short arms of two bell crank levers 20 and 21. Said levers 20 and 21 are pivotally mounted upon a supporting bracket 22 which is rigidly carried by and extends laterally from the under 85 side of the adjacent side member 5 of the frame. An outwardly directed arm 23 carried by, or formed integral with, said bracket 22 intermediate the ends of the latter has a downturned flange 24 which has its ends 90 100

turned back to form supporting lugs 25 upon which the overlying adjacent edge of the guide plate 15 may ride in its travel between the opposite limits of movement indicated in Figs. 3 and 4.

The bell crank 20 has its long arm pivotally connected to the outer end of a longitudinally disposed link 26 which has its opposite end pivotally attached to the bottom of the tray 9, or to a bar 27 which, having its opposite ends attached to said tray, underlies the latter, as shown.

Assuming that the tray 9 occupies the inwardly disposed position shown in Figs. 1 and 3, the tray is actuated to move to the outward position shown in Figs. 2 and 4 by shifting the operating lever 10 horizontally from its left-hand position toward its right-hand position. Such movement of said lever 10 actuates rotary travel of the guide plate 15 on its pivotal mounting 12. This travel, through the intermediacy of the bell-crank-carried roller 18 and the guide slot 16 in which the latter travels, actuates the bell crank 20 to swing from the position shown in Fig. 3 to that shown in Fig. 4. In such movement said bell crank, acting through the link 26, draws the transfer tray therewith. Manifestly, reverse movement of the operating lever actuates reverse travel of the aforesaid parts for returning the transfer tray to its original position.

A plate-like shield or cover 28 may be, and is preferably, employed in association with the transfer tray, it being designed that said cover shall overlie and completely conceal the tray when the latter occupies its outwardly moved position, shown in Fig. 2, during such intervals as the tray is not in use. Said cover has its opposite ends 28^a turned downwardly at right angles thereto and disposed outwardly of the lateral edges of the tray and the flanges 7 and 8 of the latter. A transverse bar 29 rigidly connects the downturned ends 28^a below the level of the tray, and pivotally attached to said bar is the inner end of a link 30 which has its opposite end pivoted to the long arm of the bell crank 21. Thus, in the final part of each swinging movement of the operating lever 10, said cover is shifted out of covering relation to the tray.

It will be noted that the slot 16 of the guide plate 15 in which is received the roller 18 through which shifting movement is imparted to the tray has its outer end portion 16^a thereof so inclined relative to the axis upon which said guide plate travels that, in the first half of the swinging movement of the operating lever from its left-hand limit of movement to its right-hand limit, a complete shifting of the tray from its inwardly disposed position, shown in Fig. 1, to its outwardly disposed position, shown in Fig. 2, is effected; whereas the inner end portion 16^b of said slot is disposed in an arc of a

circle having the pivot pin 12 as its center, thereby to permit the final half of the travel of the guide plate to be made without result so far as movement of the tray is concerned. Also, as is manifest, the first half of the return movement of the guide plate allows the tray to remain stationary, and return movement of said tray is effected alone in the final half of said return movement of said plate.

Likewise, it will be noted that in the first half of the movement of the lever 10 and plate 15 wherein the tray is shifted outwardly, as aforesaid, the roller 19 through which shifting movement is imparted to the cover 28 travels in the arc-shaped path afforded by the end portion 17^a of the slot 17, said path being in the arc of a circle having said pivot-pin 12 as its center. Thus, the cover is permitted to remain stationary until shifting of the tray has been effected, whereupon, in the final half of the travel of the guide plate, the said roller travels in the angularly disposed end portion 17^b of said slot 17, whereby force is exerted which acts to shift the cover in the direction opposite that taken by the tray in the first half of said movement.

From this, it becomes apparent that, with the tray normally located at the outer side of the window and with the cover normally disposed in overlying relation thereto, the operating lever occupies a position substantially midway between its opposite limits of movement. To permit a customer to deposit in the tray articles for transfer to the teller's side of the window, the operating lever is swung to the right from said midway position to shift the cover inwardly into uncovering relation to the tray. Then, to transfer the tray and its contents inwardly, the lever is swung to the left, which action first moves the cover into overlying relation to the tray, followed by shifting of the tray while the cover is allowed to remain stationary. Obviously, return shifting of the lever from the left-hand limit of its movement to the midway position actuates the tray to move outwardly into underlying relation to the cover.

The operating lever 10 preferably has an outer end member or section 10^a which constitutes a handle portion, such portion being telescopic therewith and being adapted, when not in use, to be inwardly thrust to a telescoped position in non-projecting relation to the adjacent edge of the counter 2.

It will be understood that various changes in the construction and arrangement of some of the parts of the hereinbefore-described structure may be made without departing from the spirit and scope of the invention as defined in the appended claims.

What is claimed is—

1. In a device of the character described, the combination with a table or counter having an opening in its top, and a closed win-

- dow disposed transversely over said opening intermediate the ends of the latter, of a trough-like receptacle slidably mounted in said opening, a stationary support carried below the path of movement of said receptacle, an operating lever pivotally mounted on said support, a cover for said receptacle slidably mounted within said opening, means intermediate said lever and said receptacle whereby manual operation of the former effects shifting of the latter from either end of said opening to the other, and means intermediate said lever and said cover whereby movement of the former effects shifting of said cover relative to said receptacle.
2. In combination with a counter having an opening in its top, and a closed window extending across the center of the opening, a tray slidable in the opening and having front and rear plates slidable on top of the counter and over the opening, a pivoted lever, a horizontal guide member rigidly secured to the lever and having a pair of spaced slots, a pair of bell crank levers each having a projection on one arm thereof engaging in the respective slots, a link pivoted to the other arm of one of the bell cranks and to the tray, a slideable cover for the tray, and a link pivoted to the cover and to the other arm of the other bell crank, said slots of the guide member having parts formed so as to cause the cover to normally lie over the tray when the latter is outside of the window and to effect inward movement of the cover to uncover the tray upon initial movement of the lever and upon further movement of said lever to move the cover over the tray and to then shift the latter to the inside of the window while the cover remains stationary.
3. In combination with a counter having an opening in its top, and a closed window extending across the center of the opening, a tray slidable in the opening, a movable cover for the tray, manual operating means, and means connected to the cover and to the tray and to the manual operating means so as to cause the cover to normally lie over the tray when the latter is outside of the window and to effect inward movement of the cover to uncover the tray upon initial movement of the operating means and upon further movement of said operating means to move the cover over the tray and to then shift the latter to the inside of the window while the cover remains stationary.
4. In combination with a counter having an opening in its top, and a closed window extending across the center of the opening, a tray slidable in the opening, a pivoted actuating member, a pair of bell cranks, a cover for the tray, means to connect the bell cranks respectively to the cover and tray, and means to actuate the bell cranks by and from said pivoted member so as to cause the cover to normally lie over the tray when the latter is outside of the window and to effect inward movement of the cover to uncover the tray upon initial movement of the operating means and upon further movement of said operating means to move the cover over the tray and to then shift the latter to the inside of the window while the cover remains stationary.
5. In combination with a counter having a closed window, a tray slidable beneath the window, a pivoted lever having one end free to provide a hand grip, a slotted member rigidly secured to the other end of the lever, a bell crank pivoted at a point spaced to one side of the lever and having a projection on one of its arms engaging in said slot of the member, and a link pivoted to the other arm of the bell crank and to the tray to slide the latter, and being located in register with said member.
- In testimony whereof, I affix my signature.
